UNITED STATES PATENT OFFICE.

JOHN AULD, OF CHICAGO, ILLINOIS.

ERASER MECHANISM.

1,034,054.

Specification of Letters Patent. Patented July 30, 1912.

Application filed July 23, 1910. Serial No. 573,574.

To all whom it may concern:

Be it known that I, JOHN AULD, a citizen of the United States, residing at Chicago, in the county of Cook and State of Illinois, 5 have invented a new and useful Eraser Mechanism, of which the following is a specification.

My invention relates to eraser mechanism, and contemplates an improved form of 10 eraser and improved construction and arrangement of supporting and holding means which will enable the eraser to be more readily adjusted and more easily manipulated.

One important object of my invention is 15 to provide an improved form for the eraser member itself which will enable it to be used with greater facility, without tiring the user, this being accomplished by providing a preferably circular eraser with a comparatively large central opening through which the tips of the thumb and forefinger can meet to form a pivot for the eraser, and which provides a radial abutment surface for the fingers.

25 Another important object is to provide supporting plates for the eraser member, which plates dip into the large central opening of the eraser to form pockets for the finger tips and an abutment surface there- 30 for. These plates may be permanently applied to the eraser or may form part of a spring holder frame, which frame may be clamped directly over the eraser member itself, or over the supporting plates thereon.

35 My invention will be better understood by reference to the following specification and the accompanying sheet of drawings, on which—

Figure 1 is a plan view of the eraser member, showing the large central opening; Fig. 2 is a sectional view of the erasing member taken on plane 2—2 Fig. 1, and showing its position with reference to the thumb and forefinger; Fig. 3 is a plan view 45 of the eraser showing supporting plates permanently applied; Fig. 4 is a sectional view taken on plane 4—4 of Fig. 3; Fig. 5 is a plan view showing a modified form of supporting means applied about the central opening; Fig. 6 is a sectional view taken on plane 6—6 Fig. 5; Fig. 7 is a plan view of the eraser member, and a removable clamping frame applied directly thereto; Fig. 8 is a plan view of the eraser member 50 with permanent supporting plates, and the removable clamping or holder frame ap-

plied thereto; Fig. 9 is a sectional view taken on plane 9—9 Fig. 7, and Fig. 10 is a sectional view taken on plane 10—10 Fig. 8.

60 The eraser member 1 is preferably circular, and has the comparatively large central opening 2, as illustrated in Fig. 2. This opening is of a diameter to allow the tips of the thumb and forefinger to meet in the 65 opening to form a pivot for the eraser member, so that it can be readily rotated to present clean surfaces. By slight pressure of the fingers, the eraser will be held in adjusted position, and the inner wall 3 of 70 the opening presents an abutment surface for the fingers to prevent radial slipping or displacement of the eraser during the process of erasing, only slight pressure of the fingers being necessary to hold the eraser 75 against rotation and to prevent radial slipping, and the eraser can therefore be manipulated with ease and accuracy without causing cramping or tiring of the fingers or hand. The main feature is, therefore, to 80 provide pockets in the eraser for receiving the finger tips to allow a firm and accurate grip to be obtained with the least exertion.

85 Erasers, particularly those for stenographers' use, are quite thin, and it is sometimes preferable to strengthen and stiffen the eraser. This I obtain without eliminating the pocket feature above referred to by providing plates over the central opening, 90 which plates have their central portions deflected to form concave pockets. As shown in Figs. 3 and 4, the circular plates 4 and 5 have the central portions 6 and 7, respectively, deflected to form the concave pockets 95 8 and 9. The plates are applied at opposite sides of the eraser-member 1 with their deflected parts extending into the opening 2 as shown. If these plates are to be permanent, a tubular rivet 10 may be applied at the centers thereof, as shown. The plates may be riveted to tightly clamp the eraser, or may be sufficiently loose to prevent harmful or deleterious pressure on the eraser, and to allow the eraser to rotate between the plates. The concave plates form pockets for the finger tips, and the surfaces 11 and 12 form the radial abutments for the fingers, so that the eraser can be easily rotated to present clean surface, and then held against rotation and against radial movement by a slight pressure of the fingers.

100 In the modified arrangement shown in

Figs. 5 and 6, the opening 2 is lined by a metallic bushing 13 of U cross section, thus leaving the opening 2 substantially free or the finger tips, while at the same time stiffening and strengthening the eraser member.

In Figs. 7 and 9 I have shown the eraser member associated with a removable holder or supporting frame F. This frame can be readily formed integrally of sheet metal, the 10 stamping blank, in the form of a band, being bent midway and the halves 14 and 15 brought together. The ends 16 and 17 of the halves are circular, and the inner sections 18 and 19 are deflected inwardly 15 abruptly to form the pockets or concavities 20 and 21. These deflected sections enter the opening 2 of the eraser member 1 when the member is slipped into the holder between the halves thereof. The spring action 20 of the holder brings the deflected sections together in the opening 2, and the eraser can then be used in the same manner as described with reference to Figs. 1 to 6, the finger tips being accommodated by the 25 pockets 20 and 21, and the inner surfaces 22 and 23 forming the abutment surface for the fingers. The spring holder allows the eraser member to be readily rotated to present clean surfaces, while a slight pressure of 30 the fingers will lock the eraser against rotational or radial displacement during the process of erasing. The same form of removable holder can also be used with the form of eraser shown in Figs. 3 and 4, or 35 that shown in Figs. 5 and 6, the concaved end sections of the holder fitting the concavities of the plates 4 and 5, or the open ends of the bushing 13. The deflected sections 18 and 19 are perforated with openings 40 24 and 25 of sufficient diameter to accommodate the rivet 10 when the form of Figs. 3 and 4 is applied to the holder, as shown in Figs. 8 and 10. The bend f of the frame F forms a convenient means for 45 supporting a brush 26. Any suitable means may be provided for clamping together the bristles of the brush, and for securing the brush in the bend. As shown, a section or tongue 27 is stamped from one of the halves

of the holder frame, and is curled inwardly 50 about the center of the brush to bind the bristles together and to lock the brush into place.

I thus provide an eraser which can be firmly clasped between the fingers with but 55 little exertion, and which has concavities for receiving the finger tips, and which provides abutments for the fingers. The eraser member itself can be used directly, or with holder plates permanently or removably applied 60 thereto, these plates having concavities to register with those of the eraser member.

Other forms and modifications besides those shown are possible which would still come within the scope of my invention, and 65 I do not desire to be limited to the precise forms shown, the main feature being the provision of concavities or pockets for receiving the fingers and for offering radial abutment surface.

I, therefore, claim the following:

In combination a U-shaped spring holder having bristles fastened in the bend thereof to form a cleaning brush and having its limbs at the ends concaved inwardly toward 75 each other to form sufficiently large pockets for finger tips, and an eraser removably inserted between said holder ends, said eraser consisting of a flat piece of composition-rubber erasing material having a central 80 opening and a concaved circular plate on each side thereof, said concaved circular plates being riveted together through said opening in such a manner as to clamp and 85 stiffen the erasing material, and being so designed as to receive and fit to the concaved portions of said U-shaped holder ends on opposite sides of the eraser, and said U-shaped holder being made of spring sheet metal whereby to cause the concaved portions of its ends to clamp said concaved circular plates and thereby rotatably support 90 the holder on the eraser.

JOHN AULD.
